UNITED STATES PATENT OFFICE

LEON BENOIT, OF CHICAGO, ILLINOIS

EGG CARTON

Original application filed October 24, 1927, Serial No. 228,304. Divided and this application filed February 6, 1930. Serial No. 426,397.

This invention relates to a collapsible holder or filler such as a carton for eggs and like commodities, being concerned particularly with certain improvements having 5 to do with interlocking of the carton components, and with the means by which the carton bottom is sustained in a desired position. The features characterizing the present invention were first disclosed in my application Serial No. 228,304 which was filed October 24, 1927, of which this application is a division.

A suggestive embodiment of my invention is illustrated in the accompanying drawing 15 in the manner following:

Figure 1 is a view in perspective showing a four-cell carton with one of its cross walls separated therefrom, as preliminary to its assembly with the remaining components;

Fig. 2 is a transverse section through the carton showing the covers thereof pressed down in closed position; and

Fig. 3 is a fragmentary detail in section taken on line 3-3 of Fig. 1.

By way of illustration, I show and describe herein a carton of that type which utilizes a blank A which is formed into a bottom, side walls, and covers, and in conjunction therewith a plurality of cross walls 20 B which provide ends and intermediate partitions. The blank is folded upon itself at 20 in its middle region and is also bendable at other points as indicated at 21, 22, 23, and 24. The general form of the blank so folded

35 is that of the letter W. The folds 22 occupy lowermost positions, the folds 23 are adjacent the upper edge of the carton, and the folds 24 are adapted to occupy substantially a center position when the blank is closed

40 over to provide covers for the carton. The bends 21 are disposed between the center and bottom folds 20 and 22, as shown. The sections of the blank between the fold 20 and bends 21 provide a vertically extending 45 double wall c. Between the bends 21 and 22 are oblique sections d, between the folds 22 and 23 are other sections e, and between the folds 23 and 24 are cover sections f. Joined to each cover section at the fold 24 is a flap 50 g. In addition the blank is adapted to be

further bent, when the carton is closed up, along the lines 31 which defines between itself and the fold 23 one additional section h which is substantially vertically disposed. In the manufacture of a blank having the 55 characteristics noted, the material, preferably a commercial fibrous product, may be scored or otherwise weakened along the lines where the several folds are to be made, so as to facilitate the operation of bending the 60 blank to the form described.

The blank is further provided upon opposite sides of its center fold with two sets of aligned slots 35 which extend between the bends 31 and 21. In line with these 65 slots are openings 36 arranged in a row along the center line of the blank. When the blank is folded upon itself along its center line, as shown in Fig. 1, these several openings take on the form of semi-circular 70 notches.

The cross wall components may desirably be of generally rectangular contour having an upper edge 40 and a bottom edge 41, with adjacent rounded corners 42. The side edges 75 or ends of these walls may extend vertically as at 43 from the bottom, and are notched at 44 so that the remaining upper portion 45 of the side edges are inset and slanted outwardly to a slight extent, if desired. Each 80 of the notches 44 is defined in part by a lug 46 which constitutes the upper end of the edge 43.

The cross walls are further characterized in each instance by the provision of two 85 sets of means either or both of which coat with the blank to secure the cross walls in assembled relation therewith. In the exemplification shown herein, each cross wall is formed with a slot 51 extending vertically 90 from its upper edge 40. A flaring entrance for the slot is provided by slanting back at 52 one edge thereof, and from the opposite slot side a lug 53 projects partly across the entrance to the slot. When a cross wall is 95 inserted through the slots 35 into final position, its lug 53, which is bent laterally during this operation, will straighten out into the proximate slot 36 to overlie the vertical 100 double wall c.

The lugs 53 and slots 35 constitute one set of means for interlocking the blank and cross walls. I provide also another set of interlocking means which serve additionally and independently to sustain the inner oblique sections of the blank intermediately in W formation, as shown in Figs. 1 and 2. Such an interlock desirably includes each cross wall wherein are provided additional slots or incisions 65 in line with the sections d of the blank. Interrupting the continuity of the slots 35 of the blank are obstructing lugs 66 adapted to be received within the slots 65 of the cross walls when the latter are assembled in position within the blank. By this means the cross walls are held in place independently of the interlock afforded by the co-operating lugs and slots 53 and 36, respectively, and additionally, the carton bottom is maintained centrally throughout its length with the inner sections of the blank sustained intermediately in the W formation shown.

The operation of assembling the cross walls B in the carton blank A may proceed as follows: The carton is first doubled upon itself along the fold line 20 so as to bring the two sets of slots 35 into register. The cross walls are then inserted into position within these slots the length of which exceeds the vertical dimension of the cross walls, and the latter are then shifted lengthwise of the blank slots so as to bring the double walled section e down toward the lower end of the cross wall slot 51. During this movement the double walled section e of the blank may be required to bend while moving past the obstructing lugs 53. In the final position, the parallel edges of the slots 51 afford support to opposite sides of the double walled section e such that it is held against tilting. The lugs 53 which project into the recesses 36 prevent a reverse movement of the blank relative to the cross walls, and the projection of the lugs 66 into the slots 65 cause the inner sections of the blank to be hooked up obliquely into the position desired for the sustaining of eggs or other commodities.

With the walls assembled into the blank in this manner, the parts are interlocked securely against displacement. For convenience in packing and shipping, the walls may be turned flat against the blank and in this knock-down condition the carton occupies but very little space. It may be set up for use by bending the blank along the folds 22 which has the effect of bringing up the sections e and h until the latter are hooked into the notches 44. With the parts so related, the lugs 46 act to retain the outer sections of the blank in a set-up condition with its upper sections f and g opened out to permit insertion of eggs or other commodities into the cells defined by the blank sections d and

e and the intervening cross walls. As these cells are filled, the obliquely disposed sections d and e will tend to bow out, in so far as permitted by the interlocking lugs and slots 66 and 65, respectively, in conformity with the contour of the eggs or other commodities so set in place. The upper portions of the blank consisting of the sections f and g may thereafter be folded over the top of the carton, the sections f meeting substantially along the center fold 20 so as to permit insertion of the two flaps g vertically into the slots 51 along one side of the double wall e.

It will be observed that the carton cover rests upon the upper horizontal edges of the several cross walls which extend vertically between the under face of the cover and the surface upon which the carton is set. The advantage of this is that when the cover flaps are pressed down into position, this vertical thrust will be resisted by the cross walls whose lower edges are in engagement with a table or other horizontal supporting surface. Due to the means provided for hooking into the oblique sections of the blank, as hereinbefore explained, a support is afforded to the carton bottom such that the latter is adequately sustained at an elevated point regardless of the load which may be introduced into the carton. The various longitudinal bends or folds in the blank provide, in effect, a plurality of hingedly connected strips forming side and bottom walls of a trough of which there are two, arranged side by side.

I claim:

1. An egg holder or filler in which is comprised a blank bent in the form of a letter W with slotted oblique bottom sections meeting at an elevated point centrally of the holder, the blank also providing front and rear sides and a cover, a plurality of cross walls collapsibly supported within the blank and extended through the slotted bottom sections thereof, and coacting means on the cross walls and oblique central bottom sections for sustaining said oblique bottom sections at a point intermediately of their upper and lower edges.

2. An egg holder or filler having a slotted blank with longitudinal bends such that it may provide a cover, front and rear sides and a bottom in which is comprised a pair of upwardly inclined transversely slotted sections meeting centrally for the length of the holder, cross walls extended vertically from the cover through the slotted bottom sections, and an interlock between the cross walls and oblique central bottom sections for sustaining said inclined bottom sections at a point intermediately of their upper and lower edges.

3. An egg holder or filler having a slotted blank with longitudinal bends such that it

may provide a cover, front and rear sides and a bottom in which is comprised a pair of upwardly inclined transversely slotted sections meeting centrally for the length of the holder, cross walls extended vertically from the cover through the slotted bottom sections, and an interlock between the cross walls and inclined central bottom sections for sustaining said inclined bottom sections at a point intermediately of their upper and lower edges, said interlock comprising means interrupting the continuity of the slots in the inclined bottom sections together with a complementary incision in the cross walls for receiving such means.

4. An egg holder or filler having a slotted blank with longitudinal bends such that it may provide a cover, front and rear sides and a bottom in which is comprised a pair of upwardly inclined transversely slotted sections meeting centrally for the length of the holder, cross walls extended vertically from the cover through the slotted bottom sections, and coacting means on the cross walls and inclined central bottom sections of the blank for sustaining said inclined bottom sections at a point intermediately of their upper and lower edges, said means comprising lugs on the one extended into incisions in the other located between the upper and lower edges of the inclined bottom sections and oppositely with respect to the longitudinal center of the holder.

5. In a collapsible egg holder, foldable trough members arranged side by side and having oppositely inclined slotted bottom sections meeting in a ridge centrally of the holder, a plurality of cross walls collapsible with the foldable trough members and extended vertically through the inclined slotted bottom sections, said cross walls and trough members being so formed as to interlock at the ridge and along the inclined central bottom sections below the ridge.

6. In an egg holder, trough members arranged side by side and meeting in a ridge centrally of the holder, said trough members having oppositely inclined slotted bottom sections, cross walls extended vertically through the slotted bottom sections and formed to embrace the trough members across the ridge and to each side thereof, and coacting means on the cross walls and oppositely inclined central bottom sections below the ridge for sustaining said sections in predetermined oblique relation.

7. In a collapsible egg holder, trough members arranged side by side and meeting in a ridge centrally of the holder, said trough members having oppositely inclined slotted bottom sections, cross walls extended vertically through the slotted bottom sections and embracing opposite sides of said trough members adjacent the ridge, and coacting means on the cross walls and oppositely in-

clined central bottom sections for sustaining said sections in predetermined oblique relation.

8. A collapsible holder or carton for eggs comprising a blank foldable along longitudinal scored lines to provide side and top wall sections and bottom wall sections oppositely and downwardly inclined from a fold or ridge disposed centrally between the side sections, said bottom wall sections being transversely slotted, and cross wall partitions extended vertically through said slotted bottom sections and individually removable therefrom, said cross wall portions being configured at their central regions to interlock with said central fold or ridge and with each of said downwardly inclined bottom sections to each side of said ridge and intermediate said ridge and the lower edges of said inclined bottom sections, whereby said cross wall partitions are securely held against individual separation from the folded blank and the diverging bottom sections sustained in predetermined oblique relation centrally between the side walls.

In testimony whereof, I have hereunto set my hand this 4th day of February, 1930.

LEON BENOIT.
